By Atty. # UNITED STATES PATENT OFFICE.

CHRISTIAN KNUDSEN, OF PORTLAND, OREGON.

DOOR-LOCK.

1,079,987.

Specification of Letters Patent.

Patented Dec. 2, 1913.

Application filed September 26, 1912. Serial No. 722,508.

To all whom it may concern:

Be it known that I, CHRISTIAN KNUDSEN, a citizen of the United States, residing in the city of Portland, county of Multnomah, and State of Oregon, have invented certain new and useful Improvements in Door-Locks, of which the following is a specification.

My invention relates to door locks, and more particularly to certain improvements in the construction and arrangement of the parts of a door lock whereby one of the knobs thereof can be moved bodily relative to the other knob for the purpose of disconnecting the latter from the bolt operating mechanism, and whereby to greatly facilitate the attachment of said lock to a door.

Among the salient objects of the invention are,—to provide in a door lock a construction whereby a round hole bored through the door transversely, near the edge thereof, and a round hole bored into the edge of the door so as to intersect the other hole, is all the preparation of the door that is required for the attachment of the lock to the door, thus avoiding the necessity of sawing or chiseling the door in order to prepare it to receive the lock; to provide a door lock in which a bolt-receiving casing, inserted into the edge of the door, intersects a knob-bar casing at right angles thereto, whereby the knob-bar, when in place, operatively intersects the bolt of said casing; to provide in a door lock a construction whereby a slight movement of one of its knobs bodily operates to render the other knob inoperative for manipulating the bolt; to provide in combination with such a door lock a key for insertion through said inoperative knob whereby to operatively connect it with the bolt-operating mechanism, and, in general, to provide an improved and practicable lock of the character referred to.

In order that others may understand my invention, I have shown on the accompanying sheet of drawings one practical embodiment thereof which I will now describe.

In the drawings,—Figure 1 is a plan view of one embodiment of the invention; Fig. 2 is a longitudinal sectional view thereof; Fig. 3 is a sectional view through the bolt casing, taken on line 3—3 of Fig. 2, showing the bolt drawn into the bolt casing; Fig. 4 is a similar view, in part, showing the position of the parts when the bolt is extended

within the bolt casing; Fig. 5 is a cross sectional view taken on line 5—5 of Fig. 2; Fig. 6 is an end view of the knob at the left of Fig. 1; Fig. 7 is a detail view of the knob-bar; Fig. 8 shows side and edge views of a key for use with the lock; and Fig. 9 is a face view of a bolt-receiving element for the door frame.

Referring now to the drawings, the lock comprises in combination a knob-bar casing 1, with knobs 2 and 3 mounted upon the ends thereof and a bolt casing 4 adapted in the present showing to be screwed into the knob-bar casing 1, at right angles thereto, as clearly indicated in Figs. 1 and 2. The knob-bar casing, as shown, is composed of two parts 1^a and 1^b, the part 1^b being screwed into the part 1^a, as at 1^c. Mounted upon said parts are two rose plates 5—5, bearing against annular shoulders 6—6, formed on said parts 1^a and 1^b, said rose plates being adapted to be pressed against the opposite sides of the door as said knob-bar casing is applied thereto. The part 1^b of said casing is provided with an inner attaching member 7, having an annular shoulder 8 formed upon its inner end, and threaded at its outer end to receive the interiorly threaded shank or neck portion of the knob 2, whereby said knob 2 is thus rotatably secured to the knob bar casing. The knob 2 is provided in its interior with an inwardly projecting bar 9, secured thereto and adapted to turn therewith, said bar 9 being provided with a longitudinally extending slit as shown in Fig. 7, also, at its inner end, transversely of said slit, with a cut 9'', Fig. 2. The knob 2 is provided in its outer end with a key opening 10 therethrough, adapted to register with the slit 9' in said member or bar 9. Knob 3 at the opposite end of said knob-bar casing 1 is provided with an overlying neck portion 3' which fits over the outer end of said part 1^b of said casing 1. Said knob also carries a shank 11, provided with two annular grooves 12 and 13, and terminates in a knob-bar 14, having a flat side, as indicated in Figs. 2, 3 and 4, and provided at its inner end with a reduced portion 15, adapted to fit into the cut 9'' made in the inner end of the bar 9, as indicated in Fig. 2, when said knob-bar 14 is fully inserted into the knob-bar casing 1. The body portion of said knob-bar 14, adjacent said reduced end portion 15, is provided at opposite sides thereof with

slits or sockets 16, which may be made of any size and depth to receive the prongs or fingers of a key specially constructed to operate therein for a purpose hereinafter 5 again referred to.

A spring actuated pawl 17 is pivotally mounted within the part 1^b of the knob-bar casing and is provided with a holding teat 17' adapted to fit into the annular grooves 12 and 13 when said knob 3 and its knob-bar 14 are inserted therein. When these parts are in the position shown in full lines in Fig. 2, it will be noted that the parts are all connected so that by turning either of 10 the knobs 2 and 3, the knob-bar 14 is turned. This is by reason of its interfitting engagement at its inner end with the bar 9, which turns with the knob 2. If now the pawl 17 be sprung and the knob 3 be pulled out- 15 wardly a short distance, as indicated in dotted lines, and so that the pawl 17 engages in the annular groove 12, the inner end of said knob-bar 14 is disconnected from the end of the bar 9, so that if knob 2 be turned it will not turn the knob-bar 14, but 20 will simply turn loosely upon the outer end of the casing 1.

In order to turn the bar 14 by means of the knob 2, from the outside, for example, 30 it is necessary to insert a special key, illustrated in Fig. 8, through said knob 2, and through the slit 9' of the bar 9 and into the slits 16 in the bar 14, at opposite sides of the reduced end portion 15 thereof. Said 35 key is provided with prong or finger portions for this purpose and these can be varied in size, shape and thickness to correspond with the kind of slits or cuts made in the end of the knob-bar 14. When the 40 key is thus inserted through knob 2 and into engagement with the inner end of the knob-bar 14, it forms a connection between the bar 9 and the bar 14, whereby the latter can be turned by means of knob 2 from the 45 outside.

The bolt casing 4 comprises a tubular member threaded exteriorly at one end and screwed into the knob-bar casing 1, at right angles thereto, in the manner indicated. 50 Said bolt casing is provided with a transverse opening adapted to register with the opening through said knob-bar casing 1, when the parts are assembled in the positions shown. Mounted within the bolt cas- 55 ing 4 is a bolt 18 provided with two openings 19 and 20 therethrough at its inner end and extending transversely of, and intersecting, each other, as indicated in Figs. 1, 3 and 4. Mounted within said openings is 60 a small operating member or element 21, having an opening 22 therethrough adapted to register with the opening 20 in the bolt 18, whereby to receive the knob-bar 14, and also it is provided with operating shoul- 65 ders 23 and 24, which rest within the open-

ings 19 in said bolt 18. The opening 22 through said operating element 21 is made flat at one side, as indicated, to fit the flat side of the knob-bar 14, whereby the turning of said bar 14 operates to turn said operating element 21 from the position shown in Fig. 4, to the position shown in Fig. 3, during which movement it engages the bolt 18 in the rear of the opening 19 therein and draws said bolt within the bolt casing 4, as indicated in Fig. 3. It is to be understood, of course, that said knob bar can be turned in either direction and the result will be the same. A coiled spring 25 in the rear of the bolt casing 4 operates to keep said bolt normally extended. 70 75 80 85 90 95

A bolt-receiving cap or pocket 26 is provided to fit into the door frame to receive the outer end of the bolt 18. This member is round, with a flange portion 27, and is exteriorly threaded as at 28 in order to be screwed into a round hole bored into the door frame. In order to facilitate the placing of said bolt-receiving element in the door frame, it is provided in its bottom with a socket 29, whereby an ordinary screw-driver can be used to place it. The bolt-receiving socket of said element is preferably made slightly oblong, as shown, in order to make provision for any settling or sagging of the door. 100

From the foregoing, it will be seen that it is only necessary to bore a round hole through the door, large enough to receive the knob-bar casing 1, and to bore another round hole into the edge of the door to intersect said first hole, and large enough to receive the bolt casing 4, and the lock can be applied to the door without further alteration or preparation of the door. It will also be noted that by pulling the knob 3 to the position shown in dotted lines, the knob-bar 14 is disconnected at its inner end from the bar 9, leaving the knob 2 free to turn without manipulating the bolt operat- 105 110 115 120 125 130

I am aware that changes can be made in the invention as here illustrated without departing from the spirit thereof and I do not, therefore, limit the invention to the particular showing here made, except as I may be limited by the hereto appended claims.

I claim:

1. A door lock comprising in combination, a cylindrical knob-bar casing, knobs and knob-bar rotatably mounted therein, a cylindrical bolt casing connected through said knob-bar casing at right angles therewith, and a bolt slidably mounted in said bolt casing and having intersecting opera- 125 130

tive connections with said knob-bar, one of said knobs being movable bodily with operative connections for rendering the other knob inoperative.

5 2. A door lock of the character referred to comprising in combination a two-part cylindrical casing, a cylindrical bolt casing screwed thereinto and extending therethrough at right angles thereto, a bolt in 10 said bolt casing, a knob-bar, with knobs, within said two-part casing, and extending through said bolt casing and bolt, with operative connections with the latter, one of said knobs being adapted to be disconnected 15 from said knob-bar by the bodily movement of the other knob, and means for holding said parts in their different positions of adjustment.

3. In a door lock, a cylindrical two-part 20 casing with rose plates, and adapted to be screwed together through the door, a cylindrical bolt casing intersecting said two-part casing and passing therethrough at right angles thereto, a bolt in said bolt casing, 25 a knob-bar with knobs in said two-part casing and operatively connected with said bolt within said bolt casing, one of said knobs being movable with the knob-bar relative to the other knob to render the latter inoperative, and a key for connecting the inoperative knob with the knob-bar.

30 4. A door lock comprising in combination, a knob-bar casing, a knob-bar with knobs rotatably mounted therein, a bolt cas-

ing intersecting said knob-bar casing and 35 screwed therethrough at right angles thereto, a bolt therein, operative connections between said knob-bar and said bolt, one of said knobs and said knob-bar being movable bodily out of operative connections with the 40 other knob for rendering said other knob inoperative, and a key for putting said inoperative knob into operative connection with said knob-bar and bolt.

5. A door lock comprising in combination 45 a two-part cylindrical casing with rose plates, a cylindrical bolt casing intersecting said two-part casing, a bolt for said bolt casing, a knob-bar with knob inserted into said two-part casing and into operative connection with said bolt, a knob rotatably mounted on the other end of said two-part casing and having a slotted bar extending into said two-part casing and adapted to be operatively connected end to end with 55 said knob-bar, said knob and knob-bar being movable bodily into and out of operative connections with said bar, and a key for insertion through said rotatably mounted knob for operatively connecting it with said 60 bodily moved knob and knob-bar, substantially as shown.

Signed at Portland, Multnomah county, Oregon, this 20th day of Sept. 1912.

CHRISTIAN KNUDSEN.
